UNITED STATES PATENT OFFICE.

JUSTUS A. TRAUT, OF NEW BRITAIN, CONNECTICUT.

DESIGN FOR A PLATE FOR SPRING-JOINTS.

SPECIFICATION forming part of Design No. 34,481, dated May 7, 1901.

Application filed January 26, 1901. Serial No. 44,948. Term of patent 14 years.

To all whom it may concern:

Be it known that I, JUSTUS A. TRAUT, a citizen of the United States, residing in New Britain, in the county of Hartford and State of Connecticut, have invented a certain new and original Design for a Plate for Spring-Joints, of which the following is a specification.

This invention relates to a design for a plate for spring-joints for folding rulers or similar articles.

The leading feature of the design is the representation of a plate, substantially as hereinafter described.

In the drawing accompanying and forming part of this specification the figure is a perspective view of a plate, showing the design.

As shown in the drawing, this design consists in a plate A, having its center *a* longitudinally pressed out and flanges *b* rising from its sides, said flanges *b* having their upper edges scalloped, said plate A being perforated through the center and having between said flanges *b* and the pressed-out center *a* projections *c*, shown as half-circles cut in the plate A and turned up. 20 25

What I claim is—

The design for a plate for spring-joints substantially as herein shown and described.

JUSTUS A. TRAUT.
